CLAIM

I claim the ornamental design for a razor, as shown and described.

DESCRIPTION

FIG. 1 is a rear perspective view of a razor of our new design;

FIG. 2 is a left side elevation view thereof, the right side view being a mirror image thereof;

FIG. 3 is a front right side perspective view thereof;

FIG. 4 is a rear right side perspective view thereof;

FIG. 5 is a front right side perspective view of a razor handle of our new design;

FIG. 6 is a front elevation view thereof,

FIG. 7 is a rear elevation view thereof,

FIG. 8 is a top plan view thereof; and,

FIG. 9 is a bottom plan view thereof.

The broken lines depict portions of the razor that form no part of the claimed design.
